UNITED STATES PATENT OFFICE.

ADDISON C. PHILPOTT, OF BUCYRUS, OHIO.

CONTROLLING SYSTEM FOR CONVEYING MEANS.

1,174,760.

Specification of Letters Patent.

Patented Mar. 7, 1916.

Application filed January 8, 1914. Serial No. 811,114.

To all whom it may concern:

Be it known that I, ADDISON C. PHILPOTT, a citizen of the United States, residing at Bucyrus, Crawford county, and State of Ohio, have invented and discovered certain new and useful Improvements in Controlling Systems for Conveying Means, of which the following is a specification.

My invention relates to car controlling system for railways or other conveying means.

The objects of the invention are to automatically propel cars or other carriers between a point of collection and a point of delivery, to provide for such travel of the carriers on a single track, to effect the automatic shifting of oppositely moving carriers to sidings in order to enable the carriers to pass one another, to provide a system adapted to carry out these objects which will dispense with individual motormen for the cars and also with the necessity of providing a special operator to control the system and which shall be inexpensive in installation and simple in construction and operation.

With these objects and others in view, my invention is embodied in preferable form in the arrangement and construction hereinafter described and illustrated in the accompanying drawings.

In these drawings, Figure 1 is a diagrammatic plan view of a preferred system of electric propulsion and control and Fig. 2 an enlarged plan view of a carrier, partly diagrammatic.

My invention is particularly applicable in its use to the transportation of material from a bed or mine to a plant where the material is to be utilized, such for instance, as clay pits or mines from which it is desired to convey the clay to the clay working or brick plant, although it is capable of application to many other uses, where it is desirable to control the propulsion, stoppage, shifting and re-starting of cars.

Referring to the drawings, 1 indicates that portion of a main track which is adjacent to a terminal where the load is to be taken on and from whence it is to be transported to a point of delivery. The cars are adapted to be propelled along this track in the direction of the arrow. The propulsive power is provided by an electric current obtained preferably from a third rail 2, which leads to a suitable source of electrical energy. This track is provided with a switch 3 which has an auto-

matic spring point permitting the cars to pass freely forward over the switch without being deflected thereby when moving in the direction of the arrow. This switch communicates with the far entrance of a siding 4 and a car is adapted to move along the siding in the opposite direction to that indicated by the arrow.

Interposed in the main line is a control rail section 6, which is insulated from the adjoining rails of the main track for the purpose of breaking the propulsive current through the motor of the car and thus stopping the car until the circuit is again established through the motor and control rail by a local circuit. Extending alongside the main track on the side opposite to that on which the third rail is placed, is a fixed contact member 7, with which is adapted to make contact a sliding shoe 8 carried by the car 9, when the car has moved to a point opposite said contact member. This car 9 is provided with a motor 10, a self-starter or automatic controlling means 11 and a shoe 12, which slides on the third rail. The car is unprovided with a motorman and is adapted to be started by throwing in the main circuit at the terminal at the point of collection or the terminal at the point of delivery. The terminal switch at each end for throwing on the main line current is indicated at 13 and this switch is adapted to be operated by one of the workmen at either of the terminals, so that the car may be initially started from the point of collection and stopped at the point of delivery by a workman at the latter point, all without the necessity of a motorman on the car or a special operator in control of the system. The switch 13 at each end serves to bridge the space between a normally dead terminal rail section and the main line.

The contact member 7 is electrically connected by a line 14 with a relay 15, which relay is also in circuit through line 16 with the third rail. The relay is also connected through wires 17 and 18 and motor and third rail with a magnet 19 preferably of the solenoid type to which the relay is adapted to transmit energy and which solenoid controls a double acting switch, the swinging blade 20 of which switch is electrically connected by wire 21 to the third rail and the two fixed contact members 22 and 23 of which switch are connected by wires 22' and 23' to the control rail section

6 of the main line and a control rail section 24 of the siding 4. The switch is made double acting by means of a spring 25, which is connected to an arm projecting from the core of the solenoid and pivoted to the latter, and which arm is provided with notches 26 and 27 adapted to engage pins 28 and 29 mounted on a cross arm 30 of the switch blade, whereby after the blade has been moved in one direction by the engagement therewith of one of the notches of the arms and the armature is released by the breaking of the circuit, the spring will act to tilt the arm 26 so as to carry the opposite notch over into engagement with its corresponding pin in position to move the switch blade in the opposite direction when the solenoid is again energized. This arm 26 is also provided with notches 30', in which the pins are adapted to fit when the arm is pulled down by the energization of the solenoid. The relay circuit is completed by the wire 31, which connects the contact 7 with a contact member 32 extending alongside the siding track 4.

The siding communicates by means of a switch 33 with the main track at a point between the place of delivery and the control rail section 6 of the main track. This switch is of such a character as to cause a car propelled from the point of delivery toward the point of collection to be deflected on to the siding.

The operation of the system is as follows: A car on the main track having been loaded at the terminal adjacent the track portion 1, the main line current is thrown on to the third rail by means of the switch 13 at said terminal and the current passing through the self-starter and motor, the car will be propelled in the direction of the arrow. Upon reaching the contact member 7, a circuit will be established through the relay and its local circuit and the solenoid will be energized, thus moving the switch blade away from the contact member 22 and throwing it into engagement with the contact member 23, whereby the controlling rail section 6 of the third rail for the main line will be cut out of circuit through the interruption of the local circuit through the switch. At the same time the dead rail section 32 of the siding third rail will be thrown into circuit with the third rail through the switch and the car. As the loaded car reaches the section 6, it will be stopped, owing to the interruption of the circuit by means of the breaking of the local circuit through the said section, and an operating circuit can only be re-established in the main line by a car on the siding. Assuming that another car has been started from the point of delivery back toward the point of collection, it will pass from the main line by the switch 33 into the near en-

trance of the siding and if no car has passed on the main track from the point of collection sufficiently far to engage with the contact member 7, then the car on the siding will be stopped by the rail control section 24, until a circuit has been established through said latter section by the contact of the car on the main track with the contact member 7, whereupon the siding car will be restarted and will move along the siding until it establishes electrical circuit through the contact member 32 and thereupon the current will be transmitted through the relay and the solenoid again energized so as to shift the switch and break the circuit through the section 32 of the siding third rail and establish it through the section 6 of the main third rail, whereupon the car on the siding will move forward over the switch to the point of collection on the main track while the other car will move forward on the main track to the point of delivery. When the loaded car reaches the point of delivery, the current may be cut off by a switch at that terminal. As there is current from the control sections through the switch only when a car is on one of such sections and since the contact members 7 and 32 are engaged by the shoe of the car only either before or after this car passes the respective control rails, there is no current from the third rail to the switch at the time of opening the same and hence arcing is prevented. It is obvious that the cars may be started at any time since one cannot move forward from the point of collection to the point of delivery until an oppositely moving car has passed along the siding.

Having thus described my invention, what I claim is:—

1. In an electric controlling system for conveying means, in combination with a main track, a siding having its opposite ends in communication with the main track between the terminals of the latter, a main track circuit, a siding track circuit self propelled carriers adapted to travel on said track and siding, and carrying self-starting means controlled by the electric circuits, switches for controlling said starting means through the main circuit, said switches located at the terminals of the main track only, means operated by a carrier on the main track for breaking the circuit through the main track and establishing the side track circuit and means operated by a carrier on the side track for establishing the main track circuit and breaking the side track circuit.

2. In an electric controlling system for conveying means, in combination with a main track and its circuit, a siding and its circuit; said siding having communication at both ends with said main track and having fixed open connections at both ends per-

mitting the automatic switching of a car traveling in one direction from the main track to the siding, a carrier receiving its propulsive power from the main circuit, 5 dead rail sections in said main track and siding, a local circuit including a solenoid, a switch, operated by said solenoid for controlling the energization of said dead rail sections, a relay for controlling the operation of said solenoid and contact means op-

erated by the carrier for establishing a circuit through the relay to operate the same.

In witness whereof, I have hereunto set my hand and seal at Indianapolis, Marion county, Indiana, this third day of January, 15

A. D. nineteen hundred and fourteen.
